[57] CLAIM

The ornamental design for a collapsible vehicular tent, as shown and described.

DESCRIPTION

FIG. 1 is a perspective view of a collapsible vehicular tent showing our new design;

FIG. 2 is a left side elevation view thereof the right side being a mirror image of that shown;

FIG. 3 is a rear elevation view thereof;

FIG. 4 is a front elevation view thereof;

FIG. 5 is a top plan view thereof;

FIG. 6 is a bottom plan view thereof; and

FIG. 7 is a perspective view of a collapsible vehicular tent showing a second embodiment of our new design the sole difference being in the addition of a rain cover it being understood that the opposite side of the rain cover is a mirror image of that shown.

The broken line showing of a fragmentary portion of a vehicle in FIGS. 1 and 7 of the drawing is for illustrative purposes only and forms no part of the claimed design.
